UNITED STATES PATENT OFFICE

PERCIVAL F. KING, OF MIAMI, FLORIDA

TENT FOR USE WITH AUTOMOBILES

Application filed July 2, 1927. Serial No. 203,089.

This invention relates to new and useful improvements in tents for use with automobiles.

One of the objects of this invention is to provide a foldable container of comparatively small dimensions which can be carried on the running board of an automobile and which when unfolded or opened will form a bed frame, in combination with a tent and a supporting structure therefor which is normally nested within the container and which may be readily raised to operative position after the container is opened.

Another object of the invention lies in the provision of a tent or shelter for the bed frame which includes side walls having inwardly extending lower portions forming shelves or article supporting portions, and to adjustably support said portions whereby ventilating openings of predetermined sizes may be created.

With these and other objects in view which will more fully appear, the nature of the invention will be more clearly understood by following the description, the appended claims, and the several views illustrated in the accompanying drawings.

In the accompanying drawings which illustrate one form of my invention,

30 Figure 1 is a view partly in elevation and partly in section showing the application of my invention to the running board of an automobile, the container being shown in its normal or closed position.

35 Figure 2 is a similar view but showing my invention in position for use.

Figure 3 is an enlarged vertical longitudinal sectional view through the assembled structure.

40 Figure 4 is a perspective view showing the upper end of one of the poles and the adjacent top supporting frame section,

Figure 5 is a vertical transverse sectional view of the assembled structure,

45 Figure 6 is a top plan view of the bed frame showing a bed spring in operative position, and showing by dotted lines the position of the tent supporting poles when the latter are nested within the respective box sections of the container, and

Figure 7 is a perspective view of the supporting poles, the top supporting frame and the hoisting cable therefor.

Like numerals designate corresponding parts throughout the several figures of the drawings.

Referring to the accompanying drawings, my invention comprises a container A which is adapted to be attached to the running board B of an automobile. The container is comparatively small and is of a foldable type and adapted to contain a bed spring C, a mattress D, a tent E, supporting poles F—F, a top supporting frame G, and a hoisting cable H. The container A is adapted to be unfolded or opened so as to form a bed frame, the bed spring is adapted to be supported on the bed frame in spaced relation to the bottom thereof. The mattress is preferably formed of two parts or sections which are adapted to be disposed in end to end relation upon the bed spring, the tent poles are adapted to be elevated into vertical positions at the opposite ends of the bed frame, and the top supporting frame is adapted to be hoisted by the cable H into position for detachable connection with the upper ends of the tent poles.

To this end, the container A consists of a pair of opposed hollow box sections 5 and 6. The section 5 includes side walls 7—7, an end or bottom wall 8, and a front wall 9. The section 6 includes side walls 10—10, an end or bottom wall 11, and a rear wall 12. The top portion of the container is closed by a top 13 which is connected by a hinge 14 with the upper edge of the front wall 9 of the section 5 and by a hinge 15 with the upper edge of the rear wall 12 of the section 6. The lower edge of the front wall 9 is connected to the running board B by a hinge 16 which preferably includes a removable pintle so as to permit the operation between the container A and the running board B. The container A is adapted to be unfolded or opened so as to dispose the sections 5 and 6 in a single horizontal plane as shown in Fig. 2, whereby said sections will form a bed frame. In order to support the bed frame thus formed, I have provided a plu-

- rality of supporting legs 17 which are pivotally connected to the respective sections so as to permit the same to be swung downwardly as shown in Figure 2.
- Disposed within the container A is the foldable bed spring C which is shown in Figs. 3 and 6 particularly. This bed spring C includes a sectional frame 18 of angle iron, the sections being indicated by the numerals 18^a and 18^b. The frame section 18^a includes side bars 19-19 and an end bar 20. The frame section 18^b includes side bars 21-21 and an end bar 22. The side bars 19 and 21 are spaced apart a distance slightly less than the depth of the container A and are connected by wires 23-23 or other flexible means. A suitable wire spring structure which I have indicated as a whole by the numeral 24 has its marginal portions connected to the sectional frames 18^a and 18^b. Each of the sectional frames is of a size to freely fit within an associated box section of the container and the flexible connections 23 are located centrally of the bed spring 25 so as to permit said bed spring to be folded within the container when the sections are folded to the position shown in Fig. 1. In order to support the bed spring C above the bottom of the bed frame, I have supported the bed spring sections 18^a and 18^b on the bed frame by means of a plurality of links 25-25, said links being disposed along the sides of the bed spring so as to permit the latter to be moved upwardly from the bottom of the bed frame to a position shown in Fig. 3. A plurality of coil springs 26 connect the end bar 20 of the bed spring with the end wall 8 of the box section 5 and tend to normally urge the bed spring to move towards said end wall 8. When it is desired to elevate the bed spring to operative position, the user pulls said spring lengthwise in a direction away from the coil spring 26 until said bed spring assumes the position shown in Fig. 6 at which time latches 27, which are carried by the end wall 11 of the box section 6, will engage the end bar 20 of said bed spring and thereby retain the same in operative position.
- Supported on the bed spring C is the mattress D which in this instance consists of two parts or sections 28-28. These mattress sections 28 are of uniform size and are adapted to be respectively positioned within the box sections of the container when the latter is in its normal or folded position.
- In order to provide shelter for the occupant of the bed, I have provided the tent E which is normally disposed within the folded or closed container. This tent includes a substantially flat top 29 and downwardly and outwardly inclined side walls 30-30. The lower portions of the side walls 30 extend inwardly to form article supporting portions or shelves 31-31, the inner edges of said portions 31 being detachably connected by snap fasteners 32, or other suitable fastening means, with the side walls of the bed frame.
- In order to support the tent E in operative position, I have provided the poles F-F and the top supporting frame G. Each pole F consists of upper and lower sections 33 and 34 which are hingedly connected as at 35. The lower end of each pole is provided with a fork 36 adapted to straddle the associated end wall 8 or 11 of the bed frame. By means of these forks 36, the poles are held against movement longitudinally of the bed frame. The lower ends of the poles are pivotally connected to the associated end walls of the bed frame so as to permit the fork 36 to be disengaged from the associated end wall of the bed frame and then swung inwardly onto the mattress D, hinge 35 permitting the pole sections to be folded in the positions shown in Fig. 6 whereby each pole will be folded and housed within the associated box section of the container. To this end, I have provided links 37-37 which are respectively pivoted at one end as at 38 to the associated end wall of the bed frame. The other end of each link is pivotally connected to the fork 36 of the associated pole through the medium of a ball and socket connection 39. The poles are normally positioned centrally between the side walls of the bed spring, and the links 37 serve to maintain said poles in these positions. When it is desired to fold each pole within the associated box section, said pole is elevated, thereby swinging the link 37 about the pivot 38. After the fork 36 has been disengaged from the associated end wall of the bed frame, the pole is moved to the left to the position shown in Fig. 6 after which the pole is folded and moved downwardly into a horizontal plane within the associated box section, this movement being permitted by reason of the ball joint 39. The upper end of each pole F is provided with an idler 40 and an inwardly extending arm 41 terminating in a socket 42.
- The top supporting frame G consists of separable sections 43-43. Each section includes a pipe 44 of a length slightly less than the length of one of the box sections. The outer end of each pipe 44 terminates in a downwardly extending hook 44^a having detachable connection with the socket 42 of the adjacent pole F. The sections 43-43 are detachably connected by a rod 45 which telescopes within the pipes 44-44 and is secured in adjusted position by means of set screws 46-46 or other suitable means. A stop pin 47 is associated with each pipe 44 so as to insure the outer end of the connecting rod 45 being always accessible. Extending outwardly from each pipe 44 are horizontally disposed U-shaped frames 48 which are each pivoted to said pipe so as to permit said frames 48 to be swung into parallelism when it is desired

to nest said frame within the container. The frames 48-48 also function to form the top 29 of the tent into a substantially flat top portion so as to increase the room within the tent.

5 The hoisting cable H has one end normally secured to a hook fixed to one of the poles F and is then trained upwardly and over the idler 40 associated with said pole. This cable 10 thence extends through guide eyes 49 and 50 formed on the respective pipes 44 of the top supporting frame G, thence over the idler 40 on the other pole, and thence downwardly to a hook carried by said other pole. It will 15 thus be seen that the top supporting frame G is connected to the hoisting cable H. Thus after the poles F have been elevated to operative positions within the tent, the top supporting frame G can then be readily elevated 20 by the hoisting cable H to its operative position when the hooks 44^a of said top supporting frame can be engaged with the sockets 42 of the pole.

In order to retain the side walls 30-30 25 in their inclined positions and to thereby provide or form the shelves 31-31, I have provided supporting arms 51. Each arm is pivotally connected as at 52 with the side wall of the bed frame and this arm extends outwardly 30 but within the tent structure as shown in Fig. 5. Hooks 53, or other suitable means, are attached to the portions 31-31 for engagement with the arms 51. When it is desired to ventilate the interior of the tent, the fasteners 32 are disengaged and the hooks 53 are moved 35 along the supporting arms 51 to the positions shown in dotted lines in Fig. 5. The shelves 31 are disposed in substantially horizontal planes and serves to support articles of clothing and the like.

40 When it is desired to fold up the entirety, the user first releases the latches 27 thus allowing the coil springs 26 to swing the bed-spring C downwardly against the bottom of 45 the bed frame. In this position, the flexible connections 23 will register with the top 18 of the container. The mattress sections are then moved in opposite directions so as to dispose 50 said sections within the respective box sections. The connecting rod 45 of the top supporting frame G is then telescoped into one of the pipes 44. The hooks 44^a of the top supporting frame G are then disconnected from the sockets 42. The top supporting frame G 55 is then lowered by means of the hoisting cable H, the respective sections of the frame being positioned within the corresponding box sections of the container. The U-shaped arms 48 of the respective top frame sections are 60 folded into parallelism. The lower portions of the side walls 30 of the tent are then folded inwardly after which the poles F are moved upwardly and are thence folded downwardly 65 to position within the respective box sections of the container after which the tent is folded

thereupon. The box section 6 is then folded over onto the box section 5 and the entirety is then swung upwardly about the hinge 16 onto the running board.

In order to properly support the top 29 70 of the tent throughout its sides, I have provided supporting arms 54-54, as shown in Fig. 7, which are pivoted to one frame 43 as at 55-55 and have hooks 56-56 at their opposite ends for detachable engagement with the other frame 43.

It is of course to be understood that the details of structure and arrangements of parts may be variously changed and modified without departing from the spirit and scope of my 80 invention.

I claim:

1. A device of the class described having means for supporting a tent in raised position including a pole, means at the lower end 85 of the pole for detachable interlocking connection with a supporting structure, and a link pivoted to the lower end of the pole and adapted for pivotal connection to the supporting structure, whereby the lower end of the pole may be detached from the supporting structure and swung about the axis of 90 the link into nested position upon the supporting structure.

2. In a device of the class described, in combination with a supporting structure, means for supporting a tent in raised position including supporting poles, a connecting means for each pole pivotally connected to the respective outer ends of the structure and to the poles, one pivotal connection of each connecting means being a universal joint, wherebv said poles may be folded and swung inwardly into nested positions within the structure.

3. In a device of the class described, means for supporting a tent in raised position including a pair of poles, means for connecting the lower ends of the poles to the opposite ends of a supporting structure, said means having substantial universal movement to permit the poles to be folded over said structure, and means connected to the upper ends of the poles for supporting the top of the tent, said top including separable 110 portions.

4. In a device of the class described, in combination with a supporting frame, means for supporting a tent in raised position including a pair of poles having their lower ends connected to the opposite ends of the frame and adapted to be folded within the frame, a separable frame detachably connected to the upper ends of the poles for supporting the top of the tent, and a hoisting cable associated with the poles and with the separable frame for elevating the latter into position for engagement with the upper ends of the poles.

5. In combination with a frame, a tent 120

thereover including a side wall extending outwardly beyond one side of the frame and then inwardly, to form a resultant article-supporting portion extending along a side edge of the frame.

5 6. In combination with a frame, a tent thereover including a side wall extending outwardly beyond a side of the frame and then inwardly to form a resultant article-supporting portion extending along a side edge of the frame, and an arm carried by the frame and extending outwardly therefrom to retain said article-supporting portion in a substantially horizontal plane.

10 7. In combination with a frame, a tent thereover having side walls extending outwardly beyond the sides of the frame and then inwardly to form resultant article-supporting portions extending along the side edges of the frame, means for detachably connecting the inner edges of the article-supporting portions with the sides of the frame, arms carried by the frame and extending outwardly therefrom to retain said article-supporting portions in substantially horizontal planes, and means carried by the article-supporting portions and connected with said arms to support said portions in ventilating positions when detached from the frame.

15 8. In combination with a frame, a tent to form a shelter for said frame, said tent having side walls extending outwardly beyond the sides of the frame and thence inwardly to form resultant article-supporting portions extending along the side edges of the frame, and arms pivotally connected to the frame and extending outwardly therefrom to retain said article-supporting portions in substantially horizontal planes, said arms being adapted to be swung within the frame.

20 35 40 In testimony whereof I hereunto affix my signature.

PERCIVAL F. KING.
